TEAR OFF CROWN

Jerry F. Scharf, Havertown, Pa., assignor to Crown Cork & Seal Company, Inc., Philadelphia, Pa., a corporation of New York

Filed June 4, 1964, Ser. No. 372,612

14 Claims. (Cl. 215—46)

The present application relates generally to container seals or closures, and more particularly to an improved tear off crown closure for containers wherein the crown closure is provided with a tear-tab having an improved score configuration.

Crown closures of the type contemplated in the instant invention and tear off closures for bottles generally, are commonly employed to effect the closure and sealing of glass bottles, narrow-necked jars and other containers, for example, those containing carbonated beverages or other liquids capable of exerting internal pressure. Typically, such containers have a circumferential radially outwardly projecting bead or shoulder having a rounded profile adjacent to and surrounding the opening or mouth of the container. Tear off closures, as known in the art, usually comprise a capsule-shaped shell of sheet metal which can be easily torn and which is adapted to be rigidly connected about the shoulder provided around the mouth of the container and thereby clamp a disc of a sealing material over the opening thereof. Commonly, a metal disc is inserted between the shell and the liner for reinforcement purposes when the tear off closure is to be utilized in sealing carbonated beverages and the like. The top of the capsule is usually flat or substantially flat and by means of shaped score lines or incisions may be provided with an integral tongue-like thumb piece formed or cut therein, hereinafter called a "tear-tab," which can easily be raised out of the top portion of the capsule and grasped by the fingers of the container user in order to tear the capsule through score lines that may be provided for this purpose and thereby open the container.

The known tear off closures described above have not found wide commercial success, however, due to difficulty in manufacture and unsatisfactory results in removing the tear-tab. For example, in the known tear off closures wherein the tear-tab is formed from a part of the closure top by means of fracturable score lines or lanced incisions, it has been found in manufacturing the same that stresses placed on the closure in the formation thereof into a capsule-shaped element, or in subsequent molding operations such as during the insertion of a sealing disc, as well as in the capping operation where the closure is sealed about the shoulder around the container mouth, the closure is subjected to lateral and transverse stresses across the top thereof which cause undesired fracturing of the score and incision lines, and induce fracture across the top of the closure itself. Also, in such closures wherein score lines define the path which the tab is to follow during tearing, these manufacturing stresses have caused severe score fracture and premature tearing of the closure, thus jeopardizing or bringing about the spoilage of the contents of the container. Another principal objection to the known tear off closures occurs in manufacturing operations wherein misalignment of the dies forming the score lines and the incisions forming the tear-tab may occur due to the extreme high speeds required for economy of production, thereby producing a closure having great resistance to removal of the tear-tab which will not easily follow the nonaligned incision and score lines. Accordingly, the art is still desirous of a means to solve the problems of premature score fracturing during formation and of aligning the incision and score lines to insure positive tracking of the tear-tab during removal.

It is therefore a principal object of this invention to provide a crown closure and tear-tab with improved score configurations.

It is another object of this invention to provide a fully effective and appealing tear off crown closure that will overcome the defects of prior art tear off closures.

It is an additional object of this invention to provide an improved tear off crown closure which is economical to produce and fully effective in sealing capacity and dependability.

It is still another object of this invention to provide an improved tear off crown closure which can be applied to existing containers to seal the same by existing production facilities without expensive modification and redesign thereof.

It is a further object of this invention to provide an improved tear off crown closure for sealing bottles containing carbonated beverages or other liquids capable of exerting internal pressure which is particularly adapted to be easily removed from the bottle without excessive effort by the fingers of the user.

It is still a further object of this invention to provide an improved tear off crown closure for glass bottles which is more economical to produce than comparable closures of the prior art and permits not only an effective tight sealing of the bottle but also readily lends itself to an unsealing thereof.

Other objects and the entire scope of the present invention, together with an appreciation of the advantages thereof, will become apparent from the following detailed description and by reference to the accompanying drawings.

Broadly stated, the objects of the invention are accomplished by providing two metal pieces, an outer shell formed from an easily fracturable metal such as aluminum and a preformed inner metal disc, for example, of steel or stainless steel press fitted to the inside of the crown, with a sealing liner, preferably a molded plastic liner applied over the disc and over a short portion of the inner side wall of the outer crown to seal the disc within the shell in a manner unexpected from the prior art. Specifically, the new tear off crown assembly of this invention consists of a basic crown shell of relatively thin aluminum formed with an incised or lanced tab in the center of the crown, wherein the tab has a circular segment shape and is redirected at the junction of its segmented circle into two short straight legs terminating at the beginning of two specially designed score configurations. The separate score configurations each begin with a small circular shape approximately located on the outer area of the top of the crown, and then immediately narrow into a thinner line score approximately extending to and over the corner radius and down the side of the crown shell, with both score lines terminating about half way down the side of the crown. Further, the separate thin preformed metal disc, which may be coated with shellac or the like, is press fitted into the crown, after which the combined crown and disc assembly is introduced into a plastic molding machine where the plastic liner is formed and secured in place over the disc and over a portion of the inner side wall of the outer crown shell and is effectively sealed thereto to hold the insert disc in place within the crown shell. The present specific score configuration, by the use of the substantially circular score area, greatly reduces score fracturing during manufacturing and crimping of the crown shell as the circular score area resists premature fracture, and also permits variations in the respective alignment of the lanced leg to the score line without jeopardizing the tear off function of the tab due to misalignment, since it has unexpectedly been found according to the invention that any fracture within the circular

score area will lead to the line scores, thus insuring positive tracking of the score to the straight leg of the lanced tab.

Referring now to the accompanying drawings which form a part hereof:

FIGURE 1 is a pictorial view of a tear off crown according to the invention as it would appear on the neck of a suitable container;

FIGURE 2 is a top view, greatly enlarged, showing the crown shell and tear-tab and score configuration;

FIGURE 3 is a diagrammatic view, greatly simplified and taken from the underside of the crown shell in FIGURE 2 to show the score configuration;

FIGURE 4 is an exploded view showing the tear off crown of the invention and the metal disc insert therefor;

FIGURE 5 is a schematic view of the tear off crown with metal insert receiving a plastisol liner in a molding operation; and

FIGURE 6 is a side elevation view, partly in section and greatly enlarged, showing the relationship of the tear off crown shell, metal insert and plastisol liner with the shoulder around the mouth of a suitable container.

Referring to FIGURE 1 of the drawings, there is shown a glass bottle or other container generally indicated at 10 that is provided with the tear off crown assembly indicated generally at 20, the same having a tear-tab generally indicated by the reference numeral 30, which tear-tab terminates in the score configurations indicated by the reference numeral 40. In the enlarged view of FIGURES 2 and 6, the uncrimped outer portion of the tear off crown assembly according to the invention is composed of the usual uncrimped or noninwardly deformed crown 20 having a generally hat-shaped metal shell 21 formed from any relatively easily fracturable metal that may be a relatively soft metal, such as aluminum. The metal shell 21 includes a slightly domed, circular top portion 22 and depending therefrom, a substantially cylindrical skirt indicated generally at 24 having a substantially smooth upper portion and terminating in an annular locking flange indicated at 26 extending radially outward of, and at substantially right angles to the cylindrical skirt 24. While the circular top portion 22 may be slightly domed so as to present slightly convex outer and inner surfaces, it will be apparent that such circular top portion can be substantially flat so as to present substantially plain outer and inner surfaces.

As best seen in FIGURE 6, the smooth upper portion of cylindrical skirt 24 merges with the circular top portion 22 of the metal crown shell in a smooth inwardly flaring annular transition portion 23 which is rounded in radial section so as to define similarly rounded annular outer and inner transition surfaces.

In order to strengthen the relatively weak crown shell 21, and to enable the new tear off crown closure 20 formed therefrom to be effectively retained in sealing engagement with the container 10 to which it is applied, the radially extending annular locking flange 26 is given an undulatory form by being circumferentially provided with a plurality of corrugations of substantially identical form. The corrugations will be seen to comprise downwardly projecting concave flutes or ribs 25 formed by radially extending downwardly converging wall portions which merge in a rounded or slightly flattened radially extending juncture, alternating with similarly shaped upwardly projecting convex ridges 27 formed by upwardly converging wall portions which merge in a rounded or slightly flattened radially extending juncture. The several corrugations shown not only add great strength and rigidity to the annular locking flange 26, but also provide for a certain amount of circumferential compression and expansion of the flange 26 which facilitates the crimping application of the tear off crown closure assembly 20. Normally, about twenty-one such corrugations are employed for the closure 20 but where the metal shell 21 is formed from lighter materials, it has been found, according to copending

application Serial No. 354,050, filed March 23, 1964, that up to forty corrugations or more, that is, forty or more ribs alternating with forty or more ridges, may be employed in order to impart the desired strength and rigidity to the closure 20. As shown, the fluted corrugations 25 each merge with the cylindrical skirt 24 in a relatively sharply rounded juncture or knee having a relatively small radius in radial section, the flutes 25 extending radially outward therefrom to the peripheral edge of the annular locking flange 26. Crimping or camming of the locking flange 26 about the shoulder of a container is facilitated by the sharp radial knee portion 28 provided approximately midway of the downwardly projecting concave flutes 25, which knee portion is adapted to be cammed under the container shoulder in a manner understood in the art.

According to the invention, the crown shell 21, as shown in FIGURE 2, is provided with the tear-tab 30 formed of a circular arc segment 31, preferably of greater than semicircular size and having reinforcing circular bosses or ribs 34 and 36 defining exterior tab portion 33 and interior tab portions 35 and 37. Although two such bosses are shown, a single such boss or a plurality may be employed to provide the reinforcing desired. The circular arc 31 terminates via relatively abrupt radii into two straight leg portions 32 and 32' which themselves terminate within the score configurations indicated by the reference numerals 40 and 40'. The straight leg portions 32 and 32' also define a tear tab portion 38, while the score configurations 40 and 40' define a further tab portion 39 which passes from the top of the shell portion 22, over the portion 23, having a radius of about one sixteenth-inch, and down the cylindrical skirt, terminating in the area of the annular locking flange. In the embodiment shown, both tab portions 38 and 39 are greater in width than the tab radius.

As shown in the sketch of FIGURE 3, taken from the underside of the crown in FIGURE 2, the lanced tab 30 is formed by making a circular arc incision 31 of preferably greater than semicircular size completely through the metal of the crown shell, the circular segment shape being redirected at the junction of the segmented circle 31 into the two short straight legs 32 and 32' terminating within the beginning of the two specially designed score configurations 40 and 40'. The score configurations 40 and 40' are each made in a manner known in the art by using dies having a substantially key shape which compress the metal to some extent and may cause it to raise slightly on the outside to provide a circular shaped portion 42 described by the arc 44. The circle 42, as an example, may have a diameter of about one-sixteenth inch and may be located on the outer area of the top of the crown. The circular portion 42 then immediately narrows into the leg or line score portion 43 formed by the lines 45 and 46. The circular portion may lie completely on the top of the crown or may run slightly over the edge thereof. The line score portion 43 is approximately .010 inch wide and extends to and over the corner radius and down the side of the crown, terminating about halfway down the side of the crown shell at the score line 48. It is to be understood that the leg portions may comprise the two lines shown which form the line score 43, or a plurality of substantially parallel score lines or may comprise a single narrow score line. The line scores 43 can also be parallel.

According to a preferred embodiment of the invention, however, the score configurations 40 and 40' are oriented with respect to each other at an angle, for example, of about 15° such that each is oriented at about 7½° from a mutual reference line. This has a first advantage of better conforming to the circular shape of the crown. As an added advantage and as a further preferred embodiment of the invention, it is desired that the line score portions 43 should reach down between the points of the ridges or nibs 27 and into the concave flutes 25 on

the periphery of the crown locking flange, as this has surprisingly been found to further reduce incidence of fracture or splitting during crimping for reasons not yet fully understood. Also according to a preferred embodiment, the straight leg portions 32 and 32' of the lanced arc 31 should desirably enter the circular portion 42 of the substantially key-shaped score configurations toward the outer extremity thereof since it has surprisingly been found according to the invention that this configuration is far less conducive to fracture during crimping and capping. It has further been found that while the leg portions 32 may be placed in substantially any area of the circle 42, as the position of the leg portions 32 is moved outwardly of the circle 42, it becomes increasingly harder to fracture the score prematurely during crimping and this is especially preferred according to the invention in reducing and resisting fracture and offering advantages in alignment. Desirably, the lanced legs 32 should not be in alignment with the line score 43, or lines 45 and 46 thereof, as these locations have been found to be more subject to fracture and splitting, although such location may be employed according to the invention.

According to the preferred embodiment, the crown shell may be formed from aluminum of about 0.0115 to 0.012 inch thickness. The entire crown may have an uncrimped outer diameter of about 1.264 inch and an inner diameter of about 1.054 inch, while the two preferred circular bosses 34 and 36 will have diameters of twenty-seven and fifteen sixty-fourths inch respectively. The crown height to the edge of the top at 21 will be about .236 inch, while the center height will be about one-quarter inch and the circular bosses will have heights of about 0.013 inch with a cross sectional radius of 0.020 inch. The diameter of the circle 31 forming the tab will be about twenty-one thirty seconds inch while the radius leading to the straight leg portions will be about one-eighth inch, and the straight legs will terminate at a distance of about three-eighths inch from a line passing through the axis of the circular tab. According to the preferred embodiment, the score configurations are about one-quarter inch long, with a one-sixteenths inch diameter circular portions and a one thirty-secondths inch radius leading into the straight leg portions, the center line of the circular portions of the two score configurations being about 0.344 inch apart.

As shown in FIGURE 4, the crown shell 21, provided with the incision and score lines shown in FIGURES 2 and 3, is assembled with a preformed metal insert 50 having a relatively flat or slightly domed internal area 52 defined by the upturned edges or slightly dished sidewall portions 54 which may have an overall height of about 0.045 inch. The insert 50, which may be formed from a relatively stiff material such as steel or stainless steel of about 0.0066 inch thickness, or a stiff aluminum is of a size to fit reasonably snugly within the crown shell 20 and may be slightly oversized to promote snug fitting engagement therein by means of press fitting. This metal insert, which forms the interior sealing surface of the new tear off crown, is adapted to receive a suitable pressure sealing resilient lining material, such as the resilient liner or gasket 70 which preferably is formed of a suitable synthetic thermoplastic material such as a polyvinyl chloride plastisol or the like. According to the invention, the insert 50 is held and sealed within the crown shell 21 principally by means of the sealing portion 74 of the resilient liner 70 which is secured by compression molding to the underside or inner surface of the tear off crown 20 and is applied over the disc, and a short portion of the inner side wall of the outer crown shell to hold the disc 50 therein. The liner material is compounded so as to be odorless and tasteless and to be free from effects on, or to be affected by, ordinary foods or liquids which may be stored in the container 10. Preferably, the liner 70

comprises a vinyl chloride plastisol such as has been illustrated and described in U.S. Patent 3,002,641.

The raised portion 72 of the plastisol liner 70 will be deformed during the capping operation, briefly described hereinafter, so as to conform to, and be in intimate sealing engagement with, the opposed sealing surface of the container or bottle. The cylindrical skirt 24 may thus be relatively shallow, i.e., of relatively short axial extent as compared to prior art closures, since it need accommodate only a relatively thin gasket or liner 70. As is understood in the art, the metal insert 50 may be provided with a suitable pre-coating of a lacquer or shellac composition to increase adhesion of the sealing liner to the metal insert but this is by no means necessary as it is known in the art that some synthetic lining materials will adhere sufficiently well to the metal insert for normal purposes.

Turning to FIGURE 5 which shows a suitable plastic molding device, generally indicated at 60, the crown shell 21, with the metal insert 50 simply placed or press fitted 20 thereto, is placed upside down into the mold form 64, which may be heated, followed by insertion of either a substantially preformed liner 70, or a mass of unformed plastisol composition in a manner known in the art. Thereafter, the die or punch 62, which may be heated, is 25 pressed against the preform or the plastisol composition, further pressing the metal insert 50 into the crown assembly and forming and plasticizing either the preform or the plastisol composition over the metal insert and into the shape of the liner 70, the plastic liner being formed 30 and secured in place over the disc and to a portion of the inner side wall of the outer crown shell 21. As shown, the liner 70 takes the shape of the crown shell skirt portion 24, the metal insert 50 and the bottom of the mold 62 to provide (see FIGURE 6) a generally flat central 35 area of about 0.006 inch thickness with a raised pressure sealing portion 72 and an exterior insert-to-crown sealing portion 74.

Turning to FIGURE 6, the tear off crown assembly 20 is shown in position prior to being shaped about the 40 shoulder portion 12 of the mouth of the container 10 by the usual capping dies. In the capping and crimping operation, the gasket or liner 70, by means of a suitable presser foot, is initially compressed between the metal of the insert 50 and the rounded, generally upwardly facing 45 sealing surface at the mouth of the bottle or container 10 to form a seal therebetween. While the seal thus established between the bottle and the crown closure is maintained, a suitable die means such as a tapered sealing throat engages the lower edge of the fluted skirt of the 50 crown closure upon axial displacement relative thereto, so as to radially compress and deform such fluted skirt portion of the closure inwardly to wedge the knee portion 28 and the lower portions of the skirt flutings under the shoulder 12, shown in cross section for convenience, and 55 thereby retain the crown closure in sealing engagement with the mouth of the container 10. This action not only provides locking engagement of the tear off crown closure with the shoulder on the container but also generally results in some further compression of the liner 60 or gasket 70. Thus, the knee portion 28 of the crown will be formed against the lower radius 18 of the shoulder 12, the shrinkage and stretching of the crown being taken up by the undulations of the locking flange portion 26. In the sealing and capping step, the portion 72 of the 65 plastisol liner 70 will be pressed against the upper radius 16 of the shoulder 12 slightly compressing the liner 70 and causing the raised portion 72 to flow inwardly. Also, the exterior sealing portion 74 will be moved close to and usually into touching engagement with the large peripheral art 14 defining the main portion of the shoulder 12. It should be understood that the present tear off 70 crown assembly can be used in conjunction with containers and bottles having other cross-sectional crown cap receiving shoulder or head shapes. One such important

improvement in bead shapes is described and claimed in said copending application, Serial No. 354,050.

In the capping and crimping operation, the tear-tab 30 will desirably raise slightly or pop up as the metal of the shell 21 is stretched to some small extent. Thereafter, the tear-tab can be gripped by the fingers of a bottle user and by a tearing action, the tear-tab will be folded back until the leg portions 32 and 32' tear into the circular portion 42 of the score configuration 40. The advantage of this circular portion is to insure that the leg portions 32 and 32' of the tear-tab will coact with at least some portion of the score configuration since, as earlier explained, poor score tracking has been a disadvantage of earlier constructions. This feature of the invention also offers an advantage in quality control since the positioning of the tear-tab and the score configurations may now be subject to some mutual variation without undesirable consequences. It is therefore to be understood that other configurations than the circular shape shown may be found suitable for this purpose and the invention should not be precisely limited thereto.

Upon reaching the circular portions or other equivalent shaped portions 42 of the score configuration, a firm pull on the tab acting through the portion 38 will cause the score configurations to tear down the leg portions formed by the score lines 45 and 46, and through the score lines 48 into the crimped flange portion 26 of the crown shell. If the pull is hard and straight, the tab 30 with portions 38 and 39 may be removed completely from the crown shell 21 such that the crown shell is torn into a C-shaped configuration and no longer retains sealing engagement with the shoulder 12 of the container 10. The remaining portions of the crown, including the shell, the metal insert and the liner, may come off with removal of the tear-tab, but if the tear-tab is pulled straight down, the shell 21, insert 50 and liner 70 can be simply removed by the fingers of the user.

Alternately, and in the more usual case, the tab 30 will be given a twisting movement as it is pulled so that, after tearing off the portion 38, the portion 39 will adhere on one side to the crown shell while the other side of portion 39 will track from one of the score portions in an arcing fashion through the annular locking flange 26. With this tearing motion and with the sealing portion 74 of the liner 70 securing the insert 50 to the crown shell, all members will adhere to tab portion 39 and be removed therewith from the mouth of the container.

In accomplishing the objects of the invention, it can be seen that a new tear off crown closure and score configuration has been provided which greatly facilitates the ease of removal of the tear-tab and insures that the tear tab will coact with the score configuration. It should be understood, however, that the detailed description and specific examples, while indicating preferred embodiments of the invention, are given by way of illustration only, since various changes and modifications can be made therein. Accordingly, the invention should only be limited to the scope of the appended claims.

What is claimed is:

1. A tear off crown closure adapted to be applied to sealingly engage the mouth of a container comprising in combination: a metal crown shell formed from relatively light gauge metal which can be easily torn, said metal shell comprising a circular top portion, a substantially cylindrical skirt depending from said circular top portion, and an integral annular locking flange extending radially outward of said cylindrical skirt, said top portion being formed with an arcuate incision providing a lanced tab, and weakened score portions located at the ends of said incision and extending therefrom, said score portions having a substantially circular shape located on the outer area of the top of said crown shell and immediately narrowing into a line score portion extending to and over the corner radius and down the cylindrical skirt, a rigid insert disc fitted into the inside of said

metal crown shell; and a resilient sealing liner secured to the inner surface of said rigid insert disc and a short portion of the inner side wall of the crown shell to secure said rigid insert within said crown shell, said liner being adapted to sealingly engage the container whereby when said crown closure is operatively applied to the container, said locking flange will retain said liner in sealing engagement with the container.

2. The structure of claim 1 wherein the metal crown shell is formed from aluminum of approximately 0.012 inch thickness.

3. The structure of claim 1 wherein the rigid insert disc is formed of stainless steel and has a substantially flat shape with slightly dished side walls.

4. The structure of claim 1 wherein said lanced tab has a circular segment shape, said tab being redirected at the junction of the segmented circle into two short straight legs terminating within the circular beginning shape of said weakened score portions.

5. The structure of claim 1 wherein the liner comprises a vinyl chloride plastisol.

6. The structure of claim 1 wherein said lanced tab is provided with plural concentric circular raised reinforcing bosses.

7. The structure of claim 1 wherein the circular shape of said score portions is approximately one-sixteenth inch in diameter and said line score portion is approximately 0.010 inch wide.

8. A tear off crown closure adapted to sealingly engage the mouth of a container having an annular crown closure receiving surface surrounding said mouth and defining the end of said container comprising in combination: a metal crown shell formed from relatively light gauge aluminum which can easily be torn, said crown shell comprising a circular top portion and a substantially cylindrical skirt depending from said circular top portion, and an integral annular locking flange extending radially outward of said cylindrical skirt, said top portion being formed with an incision providing a lanced tab in the center thereof, said tab having a circular segment shape and being redirected at the junction of the segmented circle into two short straight legs terminating within the beginning of two weakened score portions, said score portions having a substantially circular shape located on the outer area of the top of said crown shell and immediately narrowing into a line score portion extending to and over the corner radius and down the cylindrical skirt; a preformed inner stainless steel disc having a substantially flat shape with slightly dished side walls, said inner disc having substantially the same diameter as said crown shell and being press fitted thereto; and a resilient sealing liner secured to the inner surface of said inner disc and to a short portion of the inner side wall of the crown shell to secure said inner disc therein, said liner being adapted to sealingly engage the crown closure receiving surface so that when said tear off crown closure is applied by crimping to said receiving surface, said annular locking flange will engage said receiving surface to thereby retain said liner in sealing engagement with said receiving surface whereby said crown closure can be removed from sealing engagement with said receiving surface by pulling said tab through said line score portions, the circular shape of said score portions reducing score fracturing during the crimping and insuring positive tracking of the legs of the lanced tab to said score portions.

9. The structure of claim 8 wherein the aluminum shell has a thickness of about 0.0115 to 0.012 inch.

10. The structure of claim 8 wherein said score portions have a circular shape of approximately one-sixteenth inch diameter and a line score approximately 0.010 inch wide.

11. The structure of claim 8 wherein the line score of each weakened score portion terminates about half way down the side of the crown shell.

12. The structure of claim 8 wherein the liner comprises a vinyl chloride plastisol.

13. The structure of claim 8 wherein said score portions are disposed in non-parallel alignment such that the line score portions pass between the points of radially extending corrugations on said annular locking flange. 5

14. The structure of claim 8 wherein said straight legs are positioned within the outer extremities of the circular score portions such that the line score portions are not in alignment with said straight legs to thereby greatly reduce premature fracture during crimping. 10
